SYSTEM OF TRANSCRIBING FOR THE
BLIND

Enrique Rodriguez Diago, Barranquilla, Colombia

Application May 11, 1946, Serial No. 669,030

3 Claims. (Cl. 35—35)

1

This invention relates to a system of reading for the blind and has for its principal object the provision of a simple, readily learned means by which the blind may be enabled to read letters, books, or any other matter transcribed on such means.

A more particular object of the invention is to provide a cord system which may be read by the blind by means of the tactile sense.

Another object of the invention is to provide a system of the indicated type which can be learned more readily than the Braille system and which, once learned, is simpler and faster than the Braille system.

A further object of the invention is to provide a cord system for the blind which is inexpensive, can be readily provided with the transcribed matter and can be kept in a compact form when not in use.

A still further object of the invention is to provide a simple, ready means of communication between the blind.

Other objects of the invention, as well as its advantages, will become more apparent after a perusal of the following description when read in connection with the accompanying drawing, in which Fig. 1 is a plan view of a cord illustrating the alphabet employed in the invention, and Fig. 2 is a plan view of a cord provided with reading matter, the cord or string being broken to facilitate reading it by the visual sense.

In carrying out the invention, use is made of the Morse alphabet or code because it is readily learned and because a number of blind persons are already familiar with it. It will be understood however, that any other system or code may be devised for the purposes of the invention. In adopting or applying the Morse code and its modifications in the invention, the dots and dashes of such code are transcribed into knots on a cord. As will be readily seen from Fig. 1 of the drawing, the dot of the Morse code in the instant invention, is made the equivalent of a knot of a particular size and the dash of the Morse code is equivalent to a knot of greater size. Thus, where in the Morse code the letter "A" is represented by a dot and a dash, the letter "A" in the instant system is formed on the cord or string 10 by a small knot 11 and a large knot 12. In the same manner, the remainder of the letters of the alphabet (see Fig. 1) are represented on the cord 10 by groups of small and large knots corresponding to the dots and dashes, respectively, of the Morse code or its modification.

The cord 10 may be made of any suitable ma- 55 11 are continuations of, or integral with, the

2

terial which lends itself readily to the accomplishment of the invention, such as, cotton, wool, thermoplastic material, metal, etc. When using thermoplastic material or metal, it will be understood that the knots 11 and 12 may be in the form of beads attached to the cord or molded thereon in the formation of the cord. Accordingly, where the term "cord" is used in the claims, it is intended to cover ordinary cord, string, 10 twine, thermoplastic or wire filaments, etc., while where the term "knot" is used in the claims, it is intended by such expression to cover knots in the ordinary sense of the word, beads, embossments, etc. In accordance with the preferred form of the invention, the cord 10 is of usual construction on which the knots 11 and 12 are tied in the usual fashion or by means of special needle. The small knots 11 may be the usual overhand knots and are preferably made 1 mm. in diameter. 15 The larger knots 12 may be made in the form of overhand knots or figure-of-eight knots and are preferably of 3 mm. diameter. The spacing between the knots in each group forming a letter of the alphabet, except of course the knots which 20 represent the letters E and T, should be of the order of 1 cm. The interval between spaced letters in a word is preferably 3 cm., while the spacing between words may be 5 cm. The spacings between the elements of letters, letters and words 25 are illustrated in Fig. 2 of the drawings, in which the spacings designated 13 between the knots 11 and 12 which form the elements of the letter C are of the order of one centimeter, the spacings designated 14 between the letters of the word 30 "Cord" are of the order of three centimeters and the spacings designated 15 between the terminal and first letters of the words in the message "Cord system for the blind" are of the order of five centimeters. Suitable spacings are also utilized to indicate the ends of paragraphs and chapters, for example, spacings of the order of nine centimeters may be used between paragraphs, while spacings of the order of fifteen centimeters may be used between chapters. The beginnings 35 and endings of sentences may be indicated by open knots. As is illustrated in the drawings, the beginning of a phrase or sentence may be indicated by a loop knot 16 of the order of four centimeters in diameter, while the ending of the 40 phrase or sentence may be indicated by a knot 17 similar to knot 16 but having its loop cut and known as an open hand knot. Where the sentence forms part of a paragraph, it will be understood that the ends 18 of the open knots 16 and 45 17 are continuations of, or integral with, the

cord portions 10 on which are transcribed antecedent and succeeding sentences of the paragraph.

It will be understood from the foregoing, that in reading the above described cord, sightless persons have only to translate the code by pulling the cord through their fingers. Once the code is learned, the cord can be read with relatively great rapidity. When the reader finishes a cord provided with reading matter in accordance with the invention, he rolls the cord into a ball or on a spool and it is ready to read again by himself or by another reader. It will be noted that the materials utilized by this system are relatively inexpensive and that the reading matter can be transcribed thereon at relatively little cost. The code itself is quite simple and is in many cases already known by sightless persons so that the system can be employed by them without spending long periods of time in its instruction. The system also lends itself readily as a means of communication between blind persons, because of its inexpensive nature, its ready construction and its simple code.

While I have described and illustrated a preferred embodiment of my invention, it will be evident that various modifications thereof may be made and employed without departing from the spirit of the invention.

I claim:

1. A reading device for the blind comprising a flexible member having formed thereon a series of knots transcribing reading matter, said knots being arranged according to a predetermined code and being of varied form to indicate the grammatical construction of the reading matter transcribed on such member when the latter is pulled by a blind person through the fingers.

2. A reading device for the blind comprising a base member having formed thereon a series of knots transcribing reading matter, said knots

including knots of two sizes arranged according to a predetermined code to indicate letters of the alphabet and words, and knots of different form provided on said base member for indicating the beginning and ends of sentences, whereby a blind person pulling said base member through the fingers will translate the reading matter on said member.

3. A reading device such as defined in claim 2 in which the knots of two sizes are arranged according to the Morse code, the smaller sized knots being the equivalents of dots in the Morse code and the larger sized knots being the equivalents of the dashes in such code, the smaller and larger sized knots forming each word being spaced apart a distance less than the diameter of a larger sized knot, and in which an open knot of one form is provided on said base member to indicate the beginnings of sentences and in which an open knot of another form is provided on such base member to indicate the ends of sentences.
